DESIGN FOR A BINDING POST

Frank J. Coppola, East Douglas, Mass.

Application November 16, 1942, Serial No. 108,789

Term of patent 3½ years

To all whom it may concern:

Be it known that I, Frank J. Coppola, a citizen of the United States and a resident of East Douglas, in the county of Worcester and State of Massachusetts, have invented a new, original, and ornamental Design for a Binding Post, of which the following is a specification, reference being had to the accompanying drawing, forming part thereof.

Fig. 1 is a perspective view of a binding post, showing my new design,

Fig. 2 is a longitudinal, sectional view on line

2—2 of Fig. 3,

Fig. 3 is a front elevational view thereof, and

Fig. 4 is a transverse, sectional view on line

4—4 of Fig. 3.

I claim:

The ornamental design for a binding post, as shown.

FRANK J. COPPOLA.
